UNITED STATES PATENT OFFICE.

CLYDE P. EVANS, OF ST. LOUIS, AND MILFRED L. GREENSTREET AND WALLACE DAY, OF MAPLEWOOD, MISSOURI; SAID GREENSTREET AND SAID DAY ASSIGNORS TO SAID EVANS.

ANNUNCIATOR.

Application filed November 15, 1921. Serial No. 515,400.

To all whom it may concern:

Be it known that we, CLYDE P. EVANS, MILFRED L. GREENSTREET, and WALLACE DAY, citizens of the United States, residing at the city of St. Louis, Maplewood, and Maplewood, Missouri, respectively, have invented a certain new and useful Improvement in Annunciators, of which the following is a full, clear, and exact description, such as will enable others skilled in the art to which it appertains to make and use the same, reference being had to the accompanying drawings, forming part of this application, in which—

15 Figure 1 is a front elevational view of our improved annunciator.

Figure 2 is a plan view of a part of the casing frame.

Figure 3 is a vertical sectional view looking at the left hand end of the device.

Figure 4 is a vertical sectional view taken at about the center of the device.

Figure 5 is a longitudinal vertical sectional view of the device.

25 Figure 6 is a plan view of the mechanism which is arranged on the base of the annunciator.

This invention relates to a new and useful improvement in annunciators, the object 30 being to control an electric circuit with a time train whereby a signal, audible or visible, or both, will be sounded, or flashed or released, at a predetermined period or periods of time.

35 Our present invention is designed as a self-contained instrument to be used on a desk or some other appropriate object whereby the operator, or others, by positioning one or more keys may be advised by 40 sound or visible signal that a certain time has been reached.

The device is particularly adapted for giving notices of appointments or engagements, but may be used for ringing class 45 period bells, or for operating starting or quitting signals in office or factory.

In the drawings, 1 indicates a base, preferably made of wood or some other insulation material, and 2 is the casing or housing 50 which encloses the apparatus. This housing is provided with sight openings 2^a and 2^b in its front wall, through the former of which a revolving time indicating cylinder may be seen, and through the latter of 55 which positionable keys may be operated.

3 indicates frame plates extending upwardly from the base to one of which is mounted a time train mechanism indicated generally by numeral 4 to the hour staff or arbor of which is frictionally secured a cylinder 5. 60 This cylinder, as shown in Figure 2, is provided with a series of spirally arranged pins or projections 6, and the cylinder itself is provided on its periphery with a spiral division line dividing the surface of 65 the cylinder into two equal divisions, one of said divisions being preferably colored so that one portion of the cylinder is black or red and the other portion white, the line of division passing a time scale 7 located between the openings 2^a and 2^b and the color line being visible through the former. The time of day can be readily ascertained by observing through the opening 2^a the line of division, the point at which said line intersects scale 7 being the correct time. One of the divisions or spaces, and preferably 75 the one indicating the lapsed time, is black or colored so as to assist in reading the scale 7. This scale is preferably divided 80 into hours and fractions of an hour, as shown in the drawings, indicating the time between six o'clock in the morning and six o'clock in the afternoon with quarter hour intervals represented by the numerals 15, 30 and 45 between the larger hour numerals.

As shown in Figure 1, the division between the colored and uncolored spaces on cylinder 5 represents twelve o'clock noon, 90 and as the cylinder revolves in a clockwise direction, as seen from the right hand end of the apparatus, this division line will advance gradually to the afternoon periods of time. 95

This apparatus is constructed so that the cylinder 5 will make a complete revolution every twelve hours; but it is obvious that it could be so constructed as to revolve in a shorter or greater length of time, according 100 to the desires of the constructor.

8 indicates a bar arranged in juxtaposition to the cylinder 5 and insulated from plates 3 to which it is fixed, and 9 represents flat metal keys secured to and insulated from 105 the plates 3 at their lower ends and partially embracing the bar 8, their upper or inner ends being formed with shoulders whereby when said keys are pressed inwardly their upper ends will be engaged over the bar 8, 110

as shown in Figure 4, and be retained in such position until one of the pins 6 on the cylinder 5 will engage, lift and release the positioned key. These pins 6 and the keys 9 with which they co-operate are shown in the present apparatus as being successively engageable in fifteen minute periods. If the operator desires a signal to be flashed or sounded at any time within the range of the 10 hour scale, the appropriate key for that time is pressed inwardly, as shown in Figures 2 and 4. The key so positioned will be retained in its adjusted position until a pin 6 in the revolution of cylinder 5 engages the 15 inner end of the key and releases it.

10 indicates an electric battery, one pole of which is connected to a contact spring 11 by means of a wire 12 (see Figure 6). This spring 11 has its free end controlled by an 20 arm 13 extending inwardly from a door 14 mounted in the front wall of casing 2. When door 14 is closed, its arm 13 lies under a latch extension 15 on an armature 16 designed to be attracted by magnets 17 energized by the battery circuit when said circuit is closed.

The armature 16 and magnet 17 form part of a well known "buzzer", one pole of which is connected by wire 18 to a contact 19 lying 30 under spring 11, and the other pole of which is connected by a wire 20 to the metal keys 9. A contact bar 21 is located to one side of contact 19, and overlies spring 11. This bar 21 is connected by means of wire 22 to an 35 electric lamp 23 whose other terminal is connected by a wire connection 24 to wire 20 thereby completing the circuit between the lamp and metal keys 9. Hence, when the door 14 is closed, it is held closed by armature latch 15, but when the magnets are energized, the door 14 is released and permitted to swing open at the same time spring 11 rises and makes contact with the bar 21, whereby a circuit is completed through wire 40 22 and electric lamp 23 and wires 24—20 to metal keys 9, and the buzzer circuit is cut out by reason of spring 11 breaking contact with bar 19. Thus, whenever one of the pins 6 makes electric contact with a positioned key 9, the buzzer circuit will be 45 potentially completed so that when its magnets are energized, door 14 will be permitted to open, the opening movement of the door cutting out the buzzer circuit and cutting in 50 the lamp circuit so that a visible signal will be displayed.

While this is our preferred construction, it is, of course, obvious that the audible signal can be left in circuit while the visible 60 signal is displayed; but, in either event, it is desirable that the time which the audible signal is sounded or the visible signal is displayed be limited so as to save the battery. We prefer to construct the apparatus 65 above described in such a manner that when

a key 9 is set, it will require one of the pins 6 in whose path of travel it is located a predetermined time, say, five to eight minutes after the engagement of the pin with the key, before the key is released and breaks 70 the circuit thus potentially completed. It is further desirable that the signals, audible or visible, be sounded or displayed for a shorter period of time, say, five to fifteen seconds, and in order that this may be accomplished, the time train is equipped with a contact making disk or arm 25 (see Figure 3) which makes a complete revolution for each fractional portion of an hour indicated on the hour scale 7. The projection on this disk is designed to temporarily complete a circuit from the ground or framework of the mechanism and contact point 26 arranged to project through an insulation block 27 on a spring arm 28 85 suspended from an insulation block 29 secured to one of the frame plates 3. The opposite pole of the battery is connected by a wire 30 to the yielding contact 28 carrying the point 26. The bar 8 before referred to 90 is insulated from the frames 3 by means of insulation pieces 8^a and the keys 9 are insulated from the casing 2 by means of insulation strips 9^a. In this manner, when a key 9 is positioned and is engaged by a pin 95 6 to be lifted or disengaged the battery circuit is potentially completed, and during this engagement between pin 6 and key 9, the projection on disk 25 will pass the contact 26 and complete the battery circuit. As 100 stated before, the time required for a pin 6 to engage and reset one of the keys 9 may be five or eight minutes, and during this interval the projection on disk 25 will make contact with 26 and complete the buzzer circuit 105 for a period of, say, fifteen seconds. Upon the completion of the buzzer circuit, the armature will unlatch the door 14, permitting said door to drop, and consequently the free end of spring 11 will rise out of engagement with bar 19 and into engagement with bar 21 thus cutting out the buzzer circuit and cutting in the lamp circuit. 110

If it is desired that the buzzer circuit alone shall remain energized throughout the 115 period of engagement of the projection on disk 25 and contact point 26, a handle 31 (see Figure 6) may be manipulated so as to maintain contact between spring 11 and bar 19 and prevent contact between said 120 spring and bar 21.

In operation, the time train is wound by a suitable key, as usual, and the cylinder properly positioned to indicate the correct time by the division line between its colored 125 portions. If it is desired to direct attention of a person by sound or sight to a given period of time, within the range of the hour scale, the appropriate key or keys 9 are positioned. Adjacent keys may be 130

manipulated to repeat the signal. As the cylinder 5 rotates, its pins 6 will successively engage and lift the positioned keys 9, thereby potentially completing the battery circuit. While the pin 6 is in engagement with a key 9, the projection or disk 25 will pass contact 26 and complete the battery circuit thereby sounding the audible signal, opening the door 14, and flashing 10 the light, if the handle 31 permits the engagement between spring 11 and bar 21, as before described. Door 14 may be closed after a signal is sounded or flashed, as the case may be, but the closing of the door 15 does not control the sounding or flashing of subsequent signals.

The position of the door 14 is intended to direct the attention of the observer to the fact that a signal has been sounded or 20 flashed, even though the observer may not have been present at the moment.

As shown in the drawings, handle 31 occupies a position whereby spring 11 is adapted to form contact with bar 19 or bar 25 21. By moving handle 31 to the opposite position spring 11 is held out of contact with the bar 21 so that only buzzer 17 will operate.

If it is desired that the door alone operate, without action of either light or buzzer, handle 31 is moved to an intermediate position, thereby pressing spring 11 downward so that when the closing of the circuit unlatches arm 13, spring 11 will rise only 35 enough to break the contact with bar 19, and will be held by handle 31 in position midway between bars 19 and 21.

What we claim is:

1. An annunciator having a part movable 40 by a time train, a series of contacts arranged on said movable part, elements each adapted to be moved into a position in the path of movement of said contacts, an electric circuit, and a signal placed in operative position 45 upon the completion of said electric circuit by the engagement between one of said time train driven contacts and one of said elements.

2. An annunciator having a movable 50 member provided with projections sequentially arranged thereon, a clockwork mechanism for operating said movable member, an electric circuit having one terminal electrically connected to said projections, contacts 55 electrically connected to the other of said terminals and adapted to be selectively positioned to engage said projections and complete said electric circuit, and a signal operable when said electric circuit is completed.

60 3. An annunciator having a movable member provided with projections sequentially arranged thereon, a clockwork mechanism for operating said movable member, an electric circuit having one terminal electrically 65 connected to said projections, contacts cor-

responding to said projections electrically connected to the other terminal of said circuit and adapted to be selectively positioned to engage said projections and complete said electric circuit, a signal operable when said 70 electric circuit is completed, and auxiliary contacts in said circuit for limiting the operation of said signal.

4. An annunciator having a movable member provided with projections sequentially 75 arranged thereon, a clockwork mechanism for operating said movable member, an electric circuit having one terminal electrically connected to said projections, contacts, corresponding to said projections electrically 80 connected to the other terminal of said circuit and adapted to be selectively positioned to engage said projections and complete said electric circuit, a signal operable when said electric circuit is completed, and auxiliary 85 contacts in said circuit operable in time relation with the operation of said movable member and designed to restrict the operation of said signal to a predetermined period of time.

90 5. An annunciator comprising a train of gearing, a revoluble member operable thereby and provided with a plurality of contacts, an electric circuit, a signal in said circuit and a plurality of yielding members 95 each adapted to be selectively positioned to engage the corresponding contact at a given time, whereby said electric circuit is completed and operates said signal.

100 6. An annunciator comprising a train of gearing, a revoluble member operable thereby, a plurality of contacts arranged on said member, an electric circuit, a signal in said circuit, and a plurality of contact elements adapted to be selectively positioned to successively engage said contacts and complete 105 said circuit.

110 7. An annunciator comprising a train of gearing, a revoluble member operable thereby, a plurality of contacts arranged on said member, an electric circuit, a signal in said circuit, a plurality of contact elements adapted to be selectively positioned to successively engage said contacts and complete 115 said circuit, and auxiliary contacts interposed in said circuit and adapted to maintain said signal operative for a predetermined period of time.

120 8. An annunciator comprising a train of gearing, a revoluble member operable thereby and having a plurality of contact members arranged on its periphery, an electric circuit, a plurality of contact elements adapted to be positioned in co-operating positions with corresponding contact members to complete said electric circuit, a signal operable when said electric circuit is completed, and a manually operable switch for controlling said circuit.

125 9. A device of the class described com- 130

- prising a train of gearing, a cylindrical member operable thereby, a plurality of contact members arranged spirally on said cylinder, an electric circuit, a plurality of 5 contact elements adapted to be selectively positioned to successively engage said contact members and complete said circuit, a signal in said circuit, and auxiliary contact members operable by said train of 10 gearing in synchronism with said cylindrical member and adapted to control said circuit.
10. A device of the class described comprising a train of gearing, a cylindrical member operable thereby, and having a 15 plurality of contact members arranged in its periphery, an electric circuit, a plurality of contact elements adapted to be selectively locked in the path of movement of corresponding contact members, a signal operable when one of said contact members engages a corresponding contact element, and a manipulative means for controlling said circuit.
15. An annunciator comprising a train of gearing, a cylindrical member operable thereby, a plurality of contact members arranged on the periphery of said cylinder, an electric circuit, a plurality of contact 20 elements adapted to be positioned to successively engage corresponding contact members, means adapted to operate an audible signal when said electric circuit is completed by the engagement between a contact element and a corresponding contact member, and a visible signal operable by said means.
25. An annunciator comprising a train of gearing, a cylindrical member operable thereby, a plurality of contact members arranged on the periphery of said cylinder, an electric circuit, a plurality of contact elements adapted to be selectively positioned to engage said contact members, and complete said electric circuit, and a visible signal controlled by said circuit.
30. An annunciator having a part movable by a time train, contacts arranged on said movable part, elements designed to be positioned in the path of movement of said contacts, an electric circuit, an audible signal means, a visible signal means, said signal means being selectively operable upon the completion of the electric circuit by the engagement between said contacts and said elements, and manipulative means for determining the operation of said means.
35. An annunciator having a part movable by a time train, contacts arranged on said movable part, elements designed to be positioned in the path of movement of said contacts, an electric circuit, an audible signal means, a visible signal means, said signal means being operable upon the completion of the electric circuit by the engagement between said contacts and said elements.
40. An annunciator having a part movable by a time train, contacts arranged on said movable part, elements designed to be positioned in the path of movement of said contacts, an electric circuit, an audible signal means, a visible signal means, said signal means being operable upon the completion of the electric circuit by the engagement between said contacts and said elements, and manipulative means for disconnecting either one or both of said audible and visible signal means.
45. An annunciator having a part movable by a time train, contacts arranged on said movable part, elements designed to be positioned in the path of movement of said contacts, an electric circuit, an audible signal means, a visible signal means, said signal means being operable upon the completion of the electric circuit by the engagement between said contacts and said elements, and manipulative means for disconnecting either one or both of said audible and visible signal means, said signal means being operable upon the completion of the electric circuit by the engagement between said contacts and said elements.
50. An annunciator having a housing, a cylinder rotatably journaled therein, contact members spirally arranged on said cylinder, a time train gearing for operating said cylinder, an electric circuit, contact elements adapted to be successively engaged by said contact members for completing said circuit, a signal operable upon the completion of said electric circuit, and displacement means on said housing releasable by said signal.
55. An annunciator having a movable member, contact members arranged on said movable member, a time train gearing for operating said movable member, an electric circuit, contact elements designed to be successively engaged by said contact members for completing said circuit, an audible signal means operable upon the completion of said electric circuit, visible signal means, and means releasable by the operation of said audible signal means and adapted to render operative said visible signal means.
60. An annunciator having a movable member, contact members arranged on said movable member, a time train gearing for operating said movable member, an electric circuit, contact elements designed to be successively engaged by said contact members for completing said circuit, an audible signal means operable upon the completion of said electric circuit, visible signal means, and means releasable upon the operation of said audible signal means to render operative said visible signal means and disconnect said audible signal means.
65. An annunciator having a movable member, contact members arranged on said movable member, a time train of gearing for operating said movable member, an electric circuit, contact means designed to be selectively engaged by said contact members for completing said circuit, signal means operable upon the completion of said electric circuit.

circuit, and means operable in time relation with said movable member and designed to open said circuit after a given period of time.

5 20. An annunciator comprising a movable member provided with a time indicating mark, a plurality of contact members arranged on said movable member in co-operative relation with said mark, means for 10 operating said movable member, an electric circuit, a signal operable when said circuit is completed, contact elements designed to be selectively engaged by said contact members and complete said circuit, and a scale 15 having fractional hour graduations and designed to co-operate with said time indicating mark on said movable part.

21. A device of the class described com-

prising a signal, a circuit therefor, movable contacts, time train gearing for operating 20 said movable contacts, stationary contacts adapted to be selectively positioned to successively engage said movable contacts at predetermined periods of time and complete 25 said electric circuit whereby said signal is operated, and means for limiting the period of operation of said signal independently of the period of engagement between said contacts.

In testimony whereof we hereunto affix 30 our signatures this 12th day of November, 1921.
